COSMETIC HOLDER

Herman C. Schlicker, Brooklyn, N. Y., assignor to
Clairol, Inc., New York, N. Y., a corporation of
New York

Application May 23, 1940, Serial No. 336,875

8 Claims. (Cl. 132—79)

This invention relates to cosmetic holders particularly arranged for convenient storing and ready application of cosmetic sticks such as mascara, touch-up pencils, and the like.

5 In accordance with my present invention, a stick of the cosmetic material is mounted on a base which is pivoted at one end of the container, to permit ready swinging of the stick out of or back into the container. Projections are arranged on the base to limit the outward swinging movement of the stick into a predetermined extended relation. A side of the container is swung into open position to permit the extension of the cosmetic stick. The container side is thereupon closed firmly to hold the cosmetic stick in the extended position by suitable interlocking of the base thereof, as will be described in detail hereinafter.

The container and base are constructed and 20 assembled so as to provide for the removable mounting of the base with respect to the container, thereby permitting the use of refill units comprising of a cosmetic stick rigidly mounted in the base.

25 Further in accordance with my present invention, I incorporate a small cosmetic brush, in the swinging side of the cosmetic container. A preparation such as mascara or eye-shadow is arranged in the container for use with the brush.

30 The whole constitutes a miniature make-up kit which is self-contained and immediately available for use.

These and other advantages, capabilities and 35 objects of my invention will appear in the following detailed description of a specific embodiment thereof illustrated in the accompanying drawing in which:

Figure 1 is a perspective illustration of a preferred form of the cosmetic container in its 40 closed position.

Figure 2 is a perspective illustration of the cosmetic container, corresponding to Figure 1, with the cosmetic stick locked in the extended position.

45 Figure 3 is a perspective illustration of the cosmetic stick and its supporting base, as detached from the container.

50 Figure 4 is a perspective illustration of the cosmetic container showing the cosmetic stick inside the container and the side of the container in the open position.

55 Figure 5 is a vertical cross-sectional view through the cosmetic container, in closed position.

Figure 6 is a side view of the cosmetic container.

Figure 7 is a partial cross-sectional view through a section of the container of the invention as taken along the line 7—7 of Figure 6. 5

Referring to the drawing, casing 10 of the container is substantially rectangular in form and is preferably made of a plastic material. One side 11, of the casing 10 is pivoted at one end 12 thereof, exposing a corresponding side of the 10 container to permit the cosmetic stick to be extended or retracted. Projections 15 molded into side 11 and extending therefrom coact with slots 16 in the sides of the casing 10, serving as a gripping member to permit ready opening of side 11. 15 A consumable cosmetic stick 17 extends from a rigid base 18 preferably molded of a plastic material, the base and stick providing a replaceable unit.

Pins 19 extend from the sides of base 18, and 20 are inserted in corresponding openings in the side walls of container 10 for pivotally supporting cosmetic stick 17, the side walls being of sufficient resiliency to permit lateral displacement for insertion and removal of the replaceable cosmetic 25 stick unit. Cosmetic stick 17 may be of any suitable material such as touch-up composition, mascara or the like. A projection 20 extends from base 18, and is arranged for interlocking with lip 21 extending from the top edge of 30 pivoted container side 11. A recessed region 22 is formed by projection 20 of base 18 against which lip 21 of side 11 is moved as indicated in Figure 5, for locking side 11 in the closed position, and holding the cosmetic stick 17 stably in 35 the interior of the container.

When the cosmetic stick 17 is opened up to the extended position, as shown in Figure 2, projection 20 is arranged to abut the top edge 23 of container 10 to limit the swing of the cosmetic 40 stick to the upright position shown. The extended position of the cosmetic stick 17 and associated base 18 is illustrated in dotted lines in Figure 5. A transverse notch or recessed portion 24 in base 18 is arranged to coact with extending 45 lip 21 of side 11 to lock the cosmetic stick 17 in the extended position illustrated in Figure 2. The coaction of lip 21 of side 11 with the base 18 is similar to the interlocking with the base when cosmetic stick 17 is in the interior or closed 50 position. The abutment of projection 20 of base 18 against edge 23 of case 10 in conjunction with the interlocking of lip 21 with recessed portion 24 of base 18 rigidly holds the cosmetic stick 17 in the predetermined extended position, permit- 55

ting the convenient application of the cosmetic stick with container 10 serving as a holder.

A mascara brush 25 is indicated in dotted in Figure 4 recessed between mounds 26, 27 molded with side 11. A spring clip may be incorporated in mounds 26, 27 to hold mascara brush 25 in proper position when not in use. A bar of eyeshadow or other soft cosmetic material may be incorporated with the cosmetic holder of the invention to enhance the utility of the arrangement. Figure 7 illustrates eye-shadow bar at 30 extending from an insert 31 attachable to the container side 10. Figure 6 illustrates the eye-shadow bar 30 in position on container side 10, across line 7-7 of which sectional Figure 7 is taken. Alternatively, the cosmetic disk 30 may be incorporated at inner region 28 of lid 11, indicated in Figure 4.

It is to be understood that the composition of the cosmetic material for either the cosmetic stick 17 or the cosmetic disk 30 may be of any desired material for the makeup kit comprising the invention. The cosmetic stick 17 is readily removable from the container 10 across the pivotal pins 19 of its base, and may well be replaced after being consumed. Similarly, cosmetic stick 30 may be removed from side 10 through its base 31 for replacement.

Although I have described a preferred embodiment of my invention, it is to be understood that modifications as to construction, arrangement, and use may be practiced without departing from the broader spirit and scope thereof as set forth in the appended claims.

35. What I claim is:

1. A cosmetic holder comprising a casing having a longitudinal side pivoted thereon and an opening at one end, a member containing a cosmetic stick pivotally arranged at said opening, said member having a projection extending therefrom coactable with the end of said casing side when the cosmetic stick and side are in closed position to interlock the holder and stick in the closed position.

40. 2. A cosmetic holder comprising a casing having a longitudinal side pivoted thereon and an opening at one end, a member containing a cosmetic stick pivotally arranged at said opening, said member having a projection extending therefrom coactable with the end of said casing side when the cosmetic stick and side are in closed position to interlock the holder and stick in the closed position, said projection being coactable with an edge of said casing when said base is swung about to extend said cosmetic stick, to predetermine the extended position thereof.

45. 3. A cosmetic holder comprising a casing having a longitudinal side pivoted thereon and an opening at one end, a member containing a cosmetic stick pivotally arranged at said opening, said member having a projection extending therefrom coactable with an edge of said casing when said base is swung about to extend said cosmetic stick, to predetermine the extended position thereof.

50. 4. A cosmetic holder comprising a casing having a longitudinal side pivoted thereon and an opening at one end, a member containing a cosmetic stick pivotally arranged at said opening, said member having a projection extending therefrom coactable with an edge of said casing when said base is swung about to extend said cosmetic stick, to predetermine the extended position thereof.

55. 5. A cosmetic holder comprising a casing having a longitudinal side pivoted thereon and an opening at one end, a member containing a cosmetic stick pivotally arranged at said opening, said member having a projection extending therefrom coactable with an edge of said casing when said base is swung about to extend said cosmetic stick, to predetermine the extended position thereof.

from coactable with an edge of said casing when said base is swung about to extend said cosmetic stick, to predetermine the extended position thereof, said casing side engaging a notched position of said member when closed against said member while swung into said extended position for interlocking said side and base, whereby said cosmetic stick is rigidly supported extended from said casing.

5. A cosmetic holder comprising a casing having a longitudinal side pivoted thereon and an opening at one end, a base containing a cosmetic stick pivotally arranged at said opening, said base having a projection extending therefrom coactable with the end of said casing side when the cosmetic stick and side are in closed position to interlock the holder and stick in the closed position, said projection being coactable with an edge of said casing when said base is swung about to extend said cosmetic stick to predetermine the extended position thereof, said casing side engaging a transversely notched portion of said base when closed against said base while swung into said extended position for interlocking said side and base, whereby said cosmetic stick is rigidly supported extended from said casing.

6. A cosmetic holder comprising a casing having a longitudinal side pivoted thereon and an opening at one end, a base containing a cosmetic stick pivotally arranged at said opening, said base having a projection extending therefrom coactable with the end of said casing side when the cosmetic stick and side are in closed position to interlock the holder and stick in the closed position, said projection being coactable with an edge of said casing when said base is swung about to extend said cosmetic stick to predetermine the extended position thereof, said casing side engaging a transversely notched portion of said base when closed against said base while swung into said extended position for interlocking said side and base, whereby said cosmetic stick is rigidly supported extended from said casing.

7. A cosmetic holder comprising a casing having a longitudinal side pivoted thereon and an opening at one end, a base containing a cosmetic stick pivotally arranged at said opening, said base having a projection extending therefrom coactable with the end of said casing side when the cosmetic stick and side are in closed position to interlock the holder and stick in the closed position, said projection being coactable with an edge of said casing when said base is swung about to extend said cosmetic stick to predetermine the extended position thereof, a cosmetic brush removably arranged on the inside surface of said casing side and a bar of cosmetic material arranged in said casing for application with said brush.

8. A cosmetic holder comprising a casing having a longitudinal side pivoted thereon and an opening at one end, a member containing a cosmetic stick pivotally arranged at said opening, said member having a projection extending therefrom coactable with an edge of said casing when said base is swung about to extend said cosmetic stick to predetermine the extended position thereof, said casing side engaging a notched portion of said member when closed against said member while swung into said extended position for interlocking said side and base, a cosmetic brush removably arranged on the inside surface of said casing side and a replaceable bar of cosmetic material arranged in said casing for application with said brush.
